HAND WEAVING FRAME

Hyman M. Zippel, Philadelphia, Pa.

Application May 16, 1938, Serial No. 208,144

6 Claims. (Cl. 28—15)

This invention relates to a hand weaving frame, particularly designed for the looping of pile forming material with a pair of adjacent strands of twine or the like to produce strip material for the formation of rugs or similar articles.

For many years there has been practiced the formation of material in strip form for the production of rugs or the like by interlooping with a pair of strands of material such as cotton twine or the like small lengths of yarn, ribbons, rags or the like. In order to do this conveniently there have been used supports, generally of wood, provided at one end with fixedly mounted stationary twine supports, and at the other end with a strand supporting means in the form of an upwardly extending pin bifurcated at its upper end to receive and pinch and thereby hold the strand as it is finished. Intermediate the twine supports, and the supporting means just mentioned were located spaced twine tensioning means, also generally in the form of upright rods bifurcated at their upper ends to receive and yieldingly clasp and tension the twine as the loops were being applied thereto. Thus the strands were held in spaced relationship, converging toward the single strand supporting means.

It is the general object of the present invention to improve on this type of frame, which had a three-dimensional character and hence took up considerable space in storage and transportation, by providing a foldable frame formed primarily of bent pieces of wire which in folded condition is substantially flat, but which when expanded provides amply rigid parts to properly tension and support the strands which are being handled.

It is a further object of the invention to provide a frame of this general type which is of simple and inexpensive construction.

Other objects of the invention, particularly relating to details, will become apparent from the following description read in conjunction with the accompanying drawing, in which the figure represents in perspective the improved device in the expanded form in which it is used.

The improved device comprises basically a supporting trapezoid of wire having converging straight portions 2 joined at their inner ends by a transverse portion 4 and at their more distant ends by a transverse portion 6. A plate 8 has its ends inturned over the portions 2 of the wire, thus forming a relatively rigid flat base on which the holding means are mounted.

At the narrow end of the base there is provided a pivotally mounted wire holding device, indicated at 10, provided with a loop 12 between up-

wardly extending portions 14, which are adapted to normally engage each other so as to exert a clamping action on material located between them. The loop 12 relieving the bend contributes to securing a good clamping action. From the 5 clamping portions 14 the wire extends downwardly on both sides and is looped as indicated at 16 about the portion 4 of the base frame and then in reverse direction downwardly to form stop ends 18. It will be obvious from the drawing that movement of the holding device 10 is limited in a clockwise direction to a position at substantially right angles to the plate 8, while, however, it may be rotated about the wire portion 4 through about 10 270° to flatwise engagement with the bottom of 15 the plate 8. This last position is the position it may attain when the device is folded for storage or transportation.

Intermediate the ends of the base there is welded to the side portions 2 a transverse wire 20. 20 On this is mounted a supporting device 22, also of wire and similar to the supporting device 10 except that in this instance it is provided with two loops indicated at 24, each associated with clamping extensions 26. Extending downwardly from 25 these and looped about the wire 20 are portions 28, which are reversely turned, as indicated at 30, to provide stops limiting counter-clockwise motion of the means 22 to a vertical position thereof with respect to the base. By reason of 30 the limiting positions of the two holding elements 10 and 22 it will be clear that a substantial amount of tension may be exerted on the strand clamp by the two means.

A wire 32 is welded to the frame adjacent and 35 parallel to the portion 6. On this is pivoted a supporting element for balls of cord, the element comprising upright portions 34 joined by a horizontally extending portion 36. The supporting element has its wire looped about the wire 32, as 40 indicated at 38, and then reversely turned, as indicated at 40 to provide stop elements limiting clockwise movement to a vertical position with respect to the base by engagement with the portion 6 of the base. In order to completely fold the 45 device into a flat condition, the holding element just described may be turned in a counter-clockwise direction as viewed in the figure downwardly upon the side portions 2 of the base and then the holding means 22 may be folded clockwise upon it. 50 The result is a quite compact device which may be readily stored or transported.

The use will be obvious from the description and the general knowledge of the use of similar devices heretofore in use. Balls 42 of cotton 55

twine or other cord are located on the upright elements 34 and portions 44 extending therefrom are clamped as illustrated in the figure at 26 and at 14. Loops 46 are then interlaced with 5 these in the usual fashion. As the portions between 14 and 26 become filled with loops, the strands 44 may be dropped into the loops 24 and the finished portion of the product pulled out 10 of the clamping means and advanced so as to bring portions of the strands 44 substantially devoid of the loops 46 in the space between the holding means. Tension is again applied by bringing the strands 44 into the clamping portions 26 of the holding means and the operation 15 may then be resumed.

It will be clear that variations may be made in the embodiment of the invention without departing from its scope as defined in the following claims.

20 What I claim and desire to protect by Letters Patent is:

1. A weaving frame comprising a base structure, a strand holding means on said base structure, a second strand holding means on said base structure spaced from the first holding means, both of said holding means being pivoted to said base structure, and means limiting pivoting of said holding means towards each other, both holding means being pivotable in a direction 30 away from each other into flatwise relationship with the base structure.

2. A weaving frame comprising a base structure, a strand holding means on said base structure, a second strand holding means formed of wire on said base structure spaced from the first holding means, both of said holding means being pivoted to said base structure, and means limiting pivoting of said holding means towards each other, both holding means being pivotable in a 40 direction away from each other into flatwise relationship with the base structure.

3. A weaving frame comprising a base struc-

ture provided with a pair of crosswise extending wires, a strand holding means formed of wire pivoted on one of said crosswise wires, a second strand holding means pivoted on the second of said crosswise wires and spaced from the first holding means, and means limiting pivoting of said holding means towards each other, both holding means being pivotable in a direction away from each other into flatwise relationship with the base structure. 10

4. A weaving frame comprising a base structure, a strand holding means formed of wire on said base structure, a second strand holding means formed of wire on said base structure spaced from the first holding means, each of said 15 strand holding means having closely approaching parallel portions of their wire forming means for receiving and clamping strands, both of said holding means being pivoted to said base structure, and means limiting pivoting of said holding 20 means towards each other.

5. A weaving frame comprising a base structure, a strand holding means on said base structure, a second strand holding means on said base structure spaced from the first holding 25 means, both of said holding means being pivoted to said base structure, and means limiting pivoting of said holding means towards each other.

6. A weaving frame comprising a base structure, a strand holding means formed of wire on 30 said base structure, a second strand holding means formed of wire on said base structure spaced from the first holding means, each of said strand holding means comprising closely arranged substantially parallel portions of their 35 wire adapted to receive and clamp strands and each provided with a loop at the end of said closely arranged portions to provide an eye through which a strand may freely move but in which it is limited against lateral movements. 40
